United States Patent Office

Des. 229,915

Patented Jan. 15, 1974

229,915

PLACE MAT

Eugenia Bradford, 5715 S. Green St.,
Chicago, Ill. 60621

Filed Dec. 22, 1972, Ser. No. 317,697

Term of patent 14 years

Int. Cl. D6—13

U.S. Cl. D6—271

Fig. 1

Fig. 2

FIG. 1 is a top plan view of a place mat showing my new design, the broken line showing of a napkin extending from the pocket portion being for purposes of illustration only; and

FIG. 2 is a bottom edge view of the place mat.

I claim:

The ornamental design for a place mat, substantially as shown and described.
